UNITED STATES PATENT OFFICE.

JOHN E. GREEN, OF GREENVILLE, TEXAS.

APPARATUS FOR SEALING OIL WELLS.

Application filed April 2, 1928. Serial No. 266,656.

The present invention relates to an improved apparatus for sealing oil wells whereby the water in the bottom of the well will be prevented from mixing with the oil in the well.

One of the important objects of the present invention is to provide an apparatus of the above mentioned character, which will at all times be positive and efficient in its operation, the same being further simple in construction.

Other objects of the invention will become apparent as the nature of the invention proceeds and when taken in connection with the accompanying drawing.

In the accompanying drawing, forming a part of this application and in which like numerals designate like parts throughout the several views:

20 Figure 1 is a vertical sectional view through the apparatus embodying my invention showing the same in the act of being positioned in the bottom of an oil well.

Figure 2 is a similar view showing the position of the apparatus in the bottom of the well after the weighted barrel has been disengaged from the rod and supports the collapsible container or receptacle.

30 Figure 3 is a transverse section, taken approximately on the line 3—3 of Figure 1, looking in the direction of the arrows.

Figure 4 is a transverse section taken approximately on the line 4—4 of Figure 2, looking in the direction of the arrows.

35 Figure 5 is a similar section, taken on the line 5—5 of Figure 2, and

Figure 6 is a transverse section, taken on the line 6—6 of Figure 1.

40 In the drawings, wherein for the purpose of illustration is shown the preferred embodiment of my invention, the numeral 1 designates a cylindrical receptacle constructed of any suitable metal, and which is open at its upper end, a removable closure 2 being provided for the upper end of this receptacle. Formed in the lower portion of this receptacle are the spaced openings 3, the purpose of which will be hereinafter more fully described. The arrangement of the openings in 45 the lower portion of the cylindrical receptacle is more clearly shown in Figures 1 and 4 of the drawings. A flanged ring 4 is secured within the lower portion of the receptacle directly above the openings 3 to provide a seat for the disc 5 and which disc is secured on the upper end of a stem 6 that is

slidable through a central opening formed in the bottom of the receptacle and carried by the lower end of this stem is the ball shaped head 7. This ball shaped head provides a weight for normally maintaining the disc 5 seated on the flanged ring 4, whereby the cement placed in the receptacle 1 cannot escape through the openings 3, during the lowering of the apparatus in the well A.

60 Also the weight of the cement in the receptacle 1 will maintain the disc 5 in a seated position upon the flanged annular ring 4, and as more clearly shown in Figures 1 and 2 of the drawings, the receptacle 1 is of a diameter less than the diameter of the well A, so that an annular space is formed between the annular wall of the casing or receptacle and the oil well, which space is to be filled with the cement emptied from the receptacle 1, in the manner to be hereinafter more fully described.

65 Slidable through an enlarged opening formed in the removable closure 2, for the upper open end of the receptacle 1 is the tube 8, the lower end thereof being threaded externally for supporting thereon a piston or follower 9 that is adapted for reciprocatory movement in the receptacle 1 and this piston or follower is secured on the lower end portion of the tube 8 by means of the nuts 10 and 11 respectively. This construction is clearly shown in Figures 1 and 2 of the drawings.

70 Secured on the upper end of the slidable tube 3 is a relatively thick circular plate 12, the securing means therefor comprising upper and lower nuts 13 and 14, which are threaded on the upper threaded end of the tube 8, while disposed on opposite sides of the plate 12 as clearly shown in the drawings.

75 Arranged above the plate 12 is the conical shaped head 15 and secured between the inner opposed faces of the plate 12 and the head 15 are the respective ends of a collapsible receptacle 16.

80 This receptacle is preferably formed of fabric and a rubber lining 17 is arranged on the inner side of this fabric receptacle. A metallic plate 18 is secured to the upper face of the relatively thick plate 12 by the bolt 19 and the lower edge of the open ended fabric receptacle 16 is clamped between the plates 12 and 18, as clearly indicated in Figure 1. In a similar manner, the upper edge of the fabric receptacle is clamped between the bottom face of the head 15 and the metallic plate

20, the securing means between the head and this plate being shown at 21.

The receptacle 16 is partially filled with cement or other like material through a filling opening 22 formed in the head 15 and a closure plug 23 is provided for this filling opening.

Secured on the upper end of the tube or hollow piston rod 8 for disposition within the receptacle 16 is the plug 24 and slidably through this plug is the rod 25, this rod extending upwardly through the collapsible receptacle 16 and through the head 15. The rod 25 is preferably arranged in sections, the upper section of which extends through the head and the adjacent ends of the sections are threaded and connected together by means of a coupling collar 26, which engages with the inner face of the uppermost plate 20 as clearly indicated in Figures 1 and 2 of the drawings.

The lower end of the rod 25 extends through the plug 24 for slidable movement in the tube or hollow piston rod 8 and pivotally secured in a transverse slot formed in the lower end of this rod are the downwardly extending dogs 27, a pair of such dogs being provided, one being adapted to extend outwardly from one slot 28 while the other dog 30 projects outwardly from the other side of said slot and the outer ends of these pivoted dogs are pointed for engagement with the inner wall of the tube or hollow piston rod 8. An expansible coil spring 29 encircles the lower end portion of the rod 25 and a flange 30 is formed on the rod 25 at a point above the slot 28 and this coil spring 29 is disposed between the flange and the pivoted dogs 27 for normally urging the dogs outwardly into locking engagement with the tube or hollow piston rod 8, it being understood, of course, that the dogs 27 may be forced downwardly along the inner wall of the tube during the downward sliding movement of the rod 25 in said tube but said dogs will prevent the upward movement of the rod by reason of the coil spring 29 urging the pivoted dogs outwardly.

The upper end of the upper section of the rod 25 is disposed above the apex portion of the conical head 15 and is furthermore threaded for receiving the sleeve 31, which is internally threaded, the upper end of the sleeve being closed and formed with an apertured eye 32 through which is adapted to extend a break pin 33, having its ends disposed in suitable registering openings.

These registering openings are formed in the lower end of a weighted bar 34 that is suspended from a cable 35, the lower end of the weighted bar being formed with a socket 36 to receive the apertured eye portion 32 of the sleeve 31 as clearly illustrated in Figure 1.

The use of my improved apparatus may be briefly stated as follows:

Normally the parts are arranged as shown in Figure 1 of the drawings, and it is to be understood, of course, the receptacles 1 and 16 are filled with concrete or other similar material, the upper receptacle being only partially filled with this material and the entire apparatus is suspended from the cable 35 downwardly into the well A, it being understood, of course, that the brake pin 33 will support the weight of the receptacles that are filled, or contain the concrete. When the head 7 strikes the bottom of the well, the lower receptacle will be still capable of sliding downwardly on the stem 6, so that the disc 5 will be disengaged from the flanged ring 4 and the concrete in the lower receptacle will be free to flow through the openings 3 into the well and surround the receptacle 1 and after the concrete is discharged from the receptacle the follower or piston 9 will move downwardly in the receptacle, causing the tube 8 and the upper receptacle supported thereon to move downwardly in the well.

When the rod 25 has moved to its lowermost position in the tube 8, the collar 26 will rest on the upper face of the plug 24, and the weight of the concrete in the collapsible upper receptacle will cause this receptacle to assume the position shown in Figure 2, so that the side wall of the receptacle will snugly engage with the upper portion of the well, directly above the water level, so that the well will be sealed to prevent the water in the bottom of the well coming in contact with the oil that is located above the upper end of the lower receptacle 1 and by exerting sufficient pull on the cable 35, the pin 33 will become broken to permit the weighted bar 34 to be disengaged from the apertured member 32, so that said weighted bar can be entirely removed from the well and the well pumped by any conventional pumping means to remove the oil therefrom.

An oil well sealing apparatus of the above mentioned character will, at all times, be positive and efficient in its operation and will positively seal the well, so that water will be prevented from mixing with the oil. An apparatus of this character can be manufactured at a very low cost and the parts are so arranged as to enable the same to be readily and easily assembled or disassembled.

While I have shown the preferred embodiment of my invention, it is to be understood that minor changes in the size, shape, and arrangement of parts may be resorted to, without departing from the spirit of the invention and the scope of the appended claims.

Having thus described my invention, what I claim as new is:

1. An oil well sealing apparatus comprising a material receiving receptacle having discharge openings in the lower end thereof, means for cutting off communication between the discharge openings and the material in

- said receptacle, a collapsible material receiving receptacle arranged above the first mentioned receptacle, an operative connection between the receptacles, means for lowering the apparatus into a well, and means for actuating the cut-off means to permit the material to be discharged from the receptacle into the well when the bottom of the well is reached, said upper receptacle is adapted to move gradually downwardly simultaneously with the discharge of the material from the lower receptacle, the upper receptacle being collapsed for sealing engagement with the wall of the well at a predetermined place.
2. In an oil well sealing apparatus comprising a material receiving receptacle having discharge openings in the lower end thereof, means for cutting off communication between the discharge openings and the material in said receptacle, a collapsible material receiving receptacle arranged above the first mentioned receptacle, an operative connection between the receptacles, means for lowering the apparatus into a well, and means for actuating the cut-off means to permit the material to be discharged from the receptacle into the well when the bottom of the well is reached, said upper receptacle is adapted to move gradually downwardly simultaneously with the discharge of the material from the lower receptacle, the upper receptacle being collapsed for sealing engagement with the wall of the well at a predetermined place, and means to permit the release of said suspension means from the apparatus when the latter is in its lowermost position in the well.
3. In an oil well sealing apparatus, a material receiving receptacle having discharge openings in the lower end thereof, a cut-off valve in the lower end of the receptacle to prevent the discharge of the material through the discharge openings, a tube slideable through the upper end of the receptacle, a follower on the lower end of the tube for movement in the receptacle, a collapsible material receiving receptacle supported on the upper end of said tube, suspension means for the apparatus for lowering the same into the well, means for association with the valve for moving the same to an open position when the apparatus reaches the bottom of the well to permit the discharge of the material from the lower receptacle into the well, said follower and tube is adapted to move gradually downwardly in the first mentioned receptacle with the discharge of the material therefrom, the collapsible receptacle is adapted to move to a sealing position with respect to the wall of the well when the tube has reached a predetermined position.
4. In an oil well sealing apparatus, a material receiving receptacle having discharge openings in the lower end thereof, a cut-off valve in the lower end of the receptacle to prevent the discharge of the material
5. In an oil well sealing apparatus, a material receiving receptacle having discharge openings in the lower end thereof, a cut-off valve in the lower end of the receptacle to prevent the discharge of the material through the discharge openings, a tube slideable through the upper end of the receptacle, a follower on the lower end of the tube for movement in the receptacle, a collapsible material receiving receptacle supported on the upper end of said tube, suspension means for the apparatus for lowering the same into the well, means for association with the valve for moving the same to an open position when the apparatus reaches the bottom of the well to permit the discharge of the material from the lower receptacle into the well, said follower and tube is adapted to move gradually downwardly in the first mentioned receptacle with the discharge of the material therefrom, the collapsible receptacle is adapted to move to a sealing position with respect to the wall of the well when the tube has reached a predetermined position.
6. In an oil well sealing apparatus, a material receiving receptacle having discharge openings in the lower end thereof, a cut-off valve in the lower end of the receptacle to prevent the discharge of the material through the discharge openings, a tube slideable through the upper end of the receptacle, a follower on the lower end of the tube for movement in the receptacle, a collapsible material receiving receptacle supported on the upper end of said tube, suspension means for the apparatus for lowering the same into the well, means for association with the valve for moving the same to an open position when the apparatus reaches the bottom of the well to permit the discharge of the material from the lower receptacle into the well, said follower and tube is adapted to move gradually downwardly in the first mentioned receptacle with the discharge of the material therefrom, the collapsible receptacle is adapted to move to a sealing position with respect to the wall of the well when the tube has reached a predetermined position.

valve for moving the same to an open position when the apparatus reaches the bottom of the well to permit the discharge of the material from the lower receptacle into the well, said follower and tube is adapted to move gradually downwardly in the first mentioned receptacle with the discharge of the material therefrom, the collapsible receptacle is adapted to move to a sealing position with respect to the wall of the well when the tube has reached a predetermined position, a rod extending through the collapsible re-

ceptacle and movable therewith, the lower end of said rod entering the tube, and means carried by the lower end of the rod for locking the rod against upward sliding movement with respect to the tube, and a break pin connection between the upper end of the rod and said suspension means, whereby the suspension means may be released from the apparatus when the same is in its lowermost position in the well. ¹⁵ ²⁰

In testimony whereof I affix my signature.
JOHN E. GREEN.
